UNITED STATES PATENT OFFICE.

60 To all whom it may concern: MAX GRAETZ, OF BERLIN, GERMANY.

INVERTED INCANDESCENT GAS-LAMP.

65 No. 897,616. The original Specification of Letters Patent. Patented Sept. 1, 1908.

70 Application filed February 28, 1906. Serial No. 303,512.

To all whom it may concern:

Be it known that I, MAX GRAETZ, a subject of the King of Prussia, German Emperor, and resident of 92-93 Elsenstrasse, 5 Berlin, Kingdom of Prussia, German Empire, have invented certain new and useful Improvements in Inverted Incandescent Gas-Lamps, of which the following is an exact specification.

10 This invention relates to inverted incandescent gas lamps and the object of the present invention is to provide an improved incandescent gas lamp which shall work more efficiently than prior forms and at the same 15 time be simple in construction.

The invention is illustrated in the accompanying drawings in which

Figure 1 is a cross section through an improved lamp in accordance with this invention. Fig. 2 is a section on the line A—B Fig. 1. Fig. 3 is an enlarged detail of the gas nozzle regulator shown in cross section. Fig. 4 is a separate side view and Fig. 5 is a sectional plan of the regulating organ.

25 According to the form shown gas enters by a pipe nipple *a* into the regulating device the direction of the flow of the gas being shown by the arrows in Figs. 1 and 3. To this regulating device there is fixed a tube *m* 30 which in turn is fixed to a tube *b'* forming the burner tube and carrying at its lower end an enlarged piece *k* to which a porcelain burner tip *n* is fixed, a gauze or the like *t* being preferably arranged in the connection between 35 the box or tube *k* and the porcelain burner tip *n* for the purpose of giving a final thorough mixing to the gas and air which have passed in company down the burner tube *b'*. On the shoulder formed by the box *k* there 40 rest the flanges *x²* of the chimneys *x* which as can be seen from Fig. 2 are shown as two in number and of segmental cross section. The two segmental chimneys are arranged 45 opposite one another with the burner tube *b'* between so that their outer surfaces form parts of the same cylindrical surface. The lower end of the chimney is provided with a turn up *x³* as seen at the right hand of Fig. 1 in which the frame plate *i'* rests. The frame 50 plate is in the form of an inverted channel as shown with its outside flange *i²* extended downward and conveniently cut to an orna-

mental shape as shown. In this outside flange there engage the screws *w'* which support the globe *w* in the well known manner. 55 The globe *w* is closed at its lower end. The frame carrying plate is also used to support the outside casing *i* which forms a cover arranged concentrically outside the segmental chimneys with an air chamber or space 60 between.

The upper and the lower sides of casing *i* are preferably bell mouthed as shown and the lower bell mouthed part is provided with air inlet holes for permitting air circulation. 65 In this way air circulates not only in the partial annular space between the chimneys and the outer sides of the segmental chimneys which space communicates with the 70 annular space and contains the burner tube. The burner tube is thus arranged in an air circulating chamber or casing. The upper end of the chimneys also are provided with curved hood portions *x'* by which the gases 75 rising within the chimney are deflected away from the burner tube and the air inlet *m* thereto. The gas nozzle is located just above the deflecting plates *x'* of the chimneys and consists of a casing or nipple *a* in 80 which there works a hollow pin *r* provided with cross ports *e* and a bridge piece *z'* carrying a nozzle *z* which controls the opening *d'* of the gas nozzle *d*. The pin *r* is continually 85 pressed upwards by means of a spring *f* engaging on the under side of the pin head and the distance to which the pin *r* is pressed upward is regulated by means of a pointed screw *s* engaging on the upper side of the nozzle. A further screw *s²* is preferably also 90 provided for preventing the pin *r* from being entirely forced out when the adjusting screw *s* is withdrawn.

The nipple *a* is provided with an external screw which engages the tube *m* provided 95 with the air openings over which there is preferably provided a gauze *s'* to prevent the entrance of dust particles with the mixing air. The tube *m* is provided with a downwardly converging portion in which the internal mixing tube *h* is supported. Thus the gas and air entering through the nozzle *d'* and the air openings in the tube *m* respectively are intimately mixed in the tube 100.

h and pass at considerable velocity down the burner tube without coming closely in contact with the walls of the burner tube which as described above are cooled externally by the air circulating between the exterior of the chimneys and the casing *i*. In this way I provide a double security against back ignition of the gas.

The chimney *x* is also provided at its lower end with an inwardly projecting flange *i*³ on which an internal transparent tube *v* is supported practically air tight. Between the globe *w* and the internal tube *v* there is left a space for the entrance of the air necessary to complete the combustion of the mixture passing down the burner tube, the air admitted at *m* not being sufficient for complete combustion. The burner tip is provided with shoulders *g* on which the inverted incandescent gas mantle *p* is supported in the well known manner.

According to this construction the gas and pure air entering by the nozzle and air openings are thoroughly mixed while passing down through the cooled burner tube and the air for completing the combustion is pre-heated before it comes in contact with the mantle by passing in the direction of the arrows *y* round the outside of the funnel *v*. Further by means of the hoods *x'* on the chimneys the burned gases are prevented from entering the air inlets in the tube *m* and lastly by providing the funnel *v* with a practically air tight fitting to the flange *i*³ the effective length of the chimney for the combustion gases is considerably increased and in consequence, as is well understood, the draft is thereby increased and the working of the lamp rendered more efficient.

Having thus fully described the nature of my invention, what I desire to secure by Letters Patent of the United States is:—

1. An inverted incandescent lamp having in combination, segmental chimneys, a burner tube disposed in an air space between and supporting said segmental chimneys; a burner tip, a mantle supported by said burner tip, a transparent extension common to said segmental chimneys and surrounding the mantle, a globe closed at its lower end and supported from said segmental chimneys, an outer casing supported from said chimneys and leaving an air circulation space between itself and the chimneys.

2. An inverted incandescent gas lamp having in combination, a lamp casing, a plurality of chimneys of segmental cross section supporting said casing with a partially complete annular space between, a burner tube supporting said chimneys and arranged between but outside the same, a gas nozzle and air inlet piece arranged above said chimneys and attached to the burner tube, a burner tip and mantle attached to said burner tube, a trans-

parent extension common to said chimneys and surrounding said mantle.

3. An inverted incandescent gas lamp having in combination, a burner tube exposed to the atmosphere, a burner tip and mantle for said tube, segmental chimneys supported from said burner tube, a gas nozzle and air inlet above said segmental chimneys, deflecting hoods on said segmental chimneys for deflecting the burned gases away from said air inlet.

4. An incandescent gas lamp having in combination, a burner tube, a burner tip and mantle for said tube, segmental chimneys supported from said burner tube, a gas nozzle and air inlet connected to the upper part of the burner tube and above said chimneys, deflecting hoods on said chimneys for deflecting the burned gases away from said air inlet, a casing supported by said chimneys and surrounding the same so as to form an air circulating space in which said burner tube is disposed.

5. An inverted incandescent gas lamp having in combination, a burner tube, a burner tip and mantle for said tube, a plurality of chimneys of segmental cross section supported by said burner tube, a gas nozzle and air inlet piece on the burner tube and arranged above the opening of said chimneys, deflecting hoods on said chimneys opposite said air inlets, a transparent extension to said chimneys surrounding the mantle, a casing supported by said segmental chimneys and forming an air circulating space in which said burner is placed.

6. An inverted incandescent gas lamp having in combination, a burner tube exposed to the atmosphere, a burner tip and mantle for said tube, a plurality of chimneys of segmental cross section supported by said burner tube, a gas nozzle and air inlet piece on the burner tube and arranged above the opening of said chimneys, said air inlet piece having a downwardly converging end, a mixing tube with a downwardly converging mouth piece resting on said air inlet piece and projecting into the burner tube.

7. An inverted incandescent gas lamp having in combination, a gas nozzle with a regulating organ, an air inlet piece attached to said nozzle and having a downwardly converging end, a burner tube fixed to said downwardly converging end, a mixing piece with a downwardly converging mouth piece resting in said air inlet piece and projecting into said burner tube, a plurality of segmental chimneys supported from said burner tube and provided with deflecting hoods at their upper ends opposite the air inlet openings, a larger tube *k* fixed to said burner tube, a burner tip carried by said larger tube, a mantle supported by said burner tip, a lamp casing surrounding said chimneys and sup-

ported by the same so as to form an air circu-
lating casing around the chimneys, a trans-
parent extension on the chimneys and sur-
rounding the mantle, a globe with a closed
5 bottom surrounding said extension and per-
mitting of air circulation outside said exten-
sion to the mantle, substantially as described.

In witness whereof I have hereunto set my
hand in the presence of two witnesses.

MAX GRAETZ.
